UNITED STATES PATENT OFFICE

2,373,661

ELECTRON DISCHARGE VESSEL

Henry Alfred De Phillips, Belleville, N. J.

Application January 15, 1944, Serial No. 518,379

20 Claims. (Cl. 250—154)

My present invention relates to electron discharge vessels and more particularly to discharge vessels for emitting electrons into the space outside of these vessels.

It is an object of my present invention to provide an electron discharge vessel with an electron transmitting window of an entirely new type permitting passage of a relatively large percentage of the electrons created by the cathode in this vessel into the space outside of the same.

It is a further object of my present invention to provide a new type of electron transmitting windows for electron discharge vessels which are simple in construction and reliable in operation.

It is still a further object of my present invention to combine electron transmitting windows with an accelerating electrode of entirely new type in such a manner that this accelerating electrode serves for supporting and reinforcing the fragile sheet of which this window consists.

It is another object of my present invention to provide a new electron tube emitting electrons through an electron transmitting window which needs a much lower voltage and has much larger electron output than other known electron tubes of similar type.

It is still another object of my present invention to provide a new type of accelerating electrode which is arranged inside of the electron discharge vessel, e. g., electron tube, avoiding the danger of electrical shocks created by accelerating electrodes of customary type which up to now were usually arranged outside of the discharge vessel or tube.

With the above objects in view, my present invention relates to an electron discharge vessel for emitting electrons into the space outside of this vessel and mainly consists of an entirely new type of electron transmitting window in the wall of this discharge vessel; this electron transmitting window comprises, in accordance with my present invention, an extremely thin wall portion of an electron transmitting electrically nonconductive material, e. g., glass, and a flat accelerating electrode provided with a plurality of apertures for the passage of electrons arranged inside the discharge vessel adjacent to the above mentioned thin wall portion, covering the same.

This accelerating electrode might of course be shaped in the most different ways. One of the preferred embodiments of such an accelerating electrode is a very thin accelerating electrode plate provided with a great number of small apertures serving for the passage of electrons. Another embodiment of such an accelerating elec-

trode consists of a flat accelerating electrode grid forming a plurality of grid apertures through which the electrons accelerated by the grid are passing.

5 I have found that the thin electron transmitting wall portion in the wall of the discharge vessel, e. g., in the wall of the electron or cathode ray tube, is extremely fragile since it is subjected to considerable stress by the vacuum inside the 10 discharge vessel or cathode ray tube. Of course, the electron bombardment to which this thin wall portion is subjected during use also deteriorates the material of which this thin wall portion consists and causes breaking of the same after a relatively short period of use.

I have found that this thin wall portion of the discharge vessel can be substantially reinforced by sealing the above mentioned accelerating electrode to it, i. e., combining this wall portion with 20 this accelerating electrode in such a manner that they form practically a single unit. Of course, it is practically also possible to embed the accelerating electrode—particularly if it has the shape of a grid—at least partly into the thin wall portion, thereby forming a composite sheet serving 25 simultaneously as wall and electrode. Such a combined electrode and wall might be subjected to much greater stresses than not reinforced electron transmitting wall portions, so-called 30 "Lenard" windows of usual type.

In order to enable sealing of the electrode to the electron transmitting wall portion, both these parts have to be made of materials having at least substantially the same temperature co-efficient, 35 i. e., the materials of which the electrode and wall portion consist have to expand in the same way and degree when subjected to equal temperature variations.

Since the thin wall portion forming part of the 40 electron transmitting window consists preferably of an electrically non-conductive material, I make it of glass. The electrode has to be electrically conductive and therefore I use an electrically well-conductive material for making it, such as a 45 metal or an alloy. In a preferred embodiment of my new tube, I make the thin wall portion of lead glass and use an alloy comprising nickel, iron, chromium, and traces of cobalt for the accelerating electrode sealed to the same. I have 50 found that this alloy has at least substantially the same temperature co-efficient as lead glass. Thus, if such an alloy is sealed to lead glass and exposed to temperature variations within certain 55 limits, it will expand in the same way as the glass and thus not become detached from the same.

The novel features which I consider as characteristic for my invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a longitudinal section through a part of an electron discharge tube having an electron transmitting window comprising a thin wall portion and an accelerating electrode sealed thereto in accordance with my present invention;

Fig. 2 is an end view of the accelerating electrode shown in Fig. 1, seen in direction of arrow 2 on Fig. 1;

Fig. 3 is an end view of a grid-shaped embodiment of my new accelerating electrode;

Fig. 4 is a side view of an entire electron emitting vacuum tube, partly in section, provided with a modified electron transmitting window according to my present invention; and

Fig. 5 is a side view of still another modification of my new electron transmitting window particularly adapted for irradiating substances passing through an irradiating tube arranged within the discharge vessel.

As shown in Figs. 1 and 4, the evacuated electron tube 10 used for the purposes of my present invention contains electron emitting means 11 and a first accelerating electrode 12. Both these electron emitting means 11 and accelerating electrode 12 are of usual type, well-known to everybody skilled in this art, and therefore need not be described in detail. The metallic coating 13 on the inner wall of the evacuated electron tube 10 serves as second accelerating electrode and is connected with an electric circuit in well-known way by means of an electric contact 14 and an electric conductor, not shown in the drawings.

As mentioned above, I provide in wall 15 of the electron tube 10 an extremely thin wall portion 16 made of an electron transmitting electrically non-conductive material, e. g., glass. This wall portion 16 has preferably a thickness of less than one thousandth of an inch and is sealed into a corresponding opening in the wall 15 for instance in the way shown in Fig. 1.

It has been found that a window of such extreme thinness is preferably produced by separately making a glass foil thin enough for the purposes of the present invention. Such a thin glass foil can be made by blowing a glass bulb having a wall of the required thinness and then sealing a portion of this bulb wall into the open end of wall 15 of the electron tube 10. This sealing process is preferably executed by heating circular edge 17 of the opening in wall 15 and then contacting the glass tube blown in the above described way with this heated edge portion of wall 15. This contact causes the extremely thin wall of the glass tube to melt along the contacting edge and to adhere permanently to the same, thereby covering the opening at the end of the tubular wall 15 with the needed extremely thin wall portion 16.

Adjacent to this extremely thin wall portion 16 I arrange the thin plate-shaped accelerating electrode 18 shown in Fig. 2. This accelerating electrode is provided with small apertures 19 enabling passage of the electrons 20 emitted by the electron emitting means 11 and concentrated

on the accelerating electrode 18 by means of the electrodes 12 and 13.

As shown in Fig. 1, this accelerating electrode 18 is sealed to the extremely thin glass wall portion 16 supporting and reinforcing the same as well as to the adjacent wall portion 21 of the tubular wall 15 of electron tube 10. This accelerating electrode 18 is connected with the corresponding contact member 23 by the conductor 10 22 in the usual manner. This contact 23 is then connected with an electric circuit supplying the accelerating current for the accelerating electrode 18.

I wish to mention that I might produce an 15 electron transmitting window of the above described type also by first inserting into the opening at the end of the tubular wall 15 the accelerating electrode 18, heating the same and thereafter contacting a thin glass foil of the type described above with the outer surface of the thus arranged heated electrode 18, thus causing this glass foil to melt and to adhere to the electrode 18 and the edge 17 of the tubular wall 15. In this case, part of the molten glass will enter the 20 apertures 19, thus forming a single composite unit consisting of the electrode 18 and the glass foil 16 partly penetrating into and filling the apertures 19 in the electrode and firmly adhering to the same.

25 As mentioned above, I might use also a grid-shaped electrode 24 of the type shown in Fig. 3 instead of the plate-shaped electrode 18 for the purposes of my present invention. Such a grid-shaped electrode is then arranged in the same 30 way as the plate-shaped electrode shown in Fig. 1 and thus need not be described in detail. I wish only to mention that it is important that the wires or narrow straps 25 of which this grid 24 consists are connected with each other at 35 their intersection points in such a manner as to form one single electrically conductive unit. Of course, such a grid-shaped accelerating electrode will also concentrate the electrons 20 so as to force them through the grid apertures 26 40 against and through the thin glass wall 16 behind the grid. In case such a grid is used as accelerating electrode, it might be made of extremely thin wire and practically embedded into the thin glass wall 16, thus forming a combined 45 wire reinforced glass wall portion serving as accelerating electrode.

In Fig. 4 another embodiment of an electron tube with an electron transmitting window of the new type proposed by me is shown. In this 50 tube, the electron emitting means are provided in the usual way. However, the electron transmitting window 27 is not arranged in the wall 15 of the tube but I provide an additional glass tube 28 sealed into a corresponding opening 29 of the tubular wall 15 as shown at the top of Fig. 4. The bottom part of this tube 28 consists of an extremely thin wall portion 30. The cup-shaped accelerating electrode 31 is placed over the bottom portion of the tube 28 entirely enclosing the same and sealed to the wall of this tube 28 as well as to the thin wall portion 30 at the bottom of the same in the way described above. Of course, this electrode 31 is also provided with small apertures 32 of the type described above and thus operates in the same way as the electrode shown in Figs. 2 and 3. This 55 embodiment of my present invention enables placing of substance, e. g., fluid, into tube 28 and irradiation of the same by electrons while the irradiated substance is arranged in direct contact

with the electron transmitting wall portion 30 of this tube.

The embodiment shown in Fig. 5 is particularly adapted for irradiating fluids during passage of the same through an irradiating tube 32 arranged within electron tube 10. For this purpose, this irradiating tube 32 is connected with an inlet tube 33 and an outlet tube 34 and all three tubes are sealed into the wall 15 of the electron tube 10 in the way shown in Fig. 5. In the wall of the irradiating tube 32, I provide an extremely thin glass wall portion 35 of the type described above. This glass wall portion 35 and the adjacent portions of the outer surface of irradiating tube 32 are covered by a semi-cylindrical accelerating electrode 36 of the type described. Of course, this accelerating electrode 36 is sealed to the thin glass wall portion 35 and to the adjacent wall portions of irradiating tube 32 in the way explained and described above. By means of conductor 37 this accelerating electrode 36 is connected to contact 38 which in turn is connected to an electric circuit supplying the needed accelerating current by a conductor not shown in the drawings.

It will be understood that each of the elements described above, or two or more together, may also find a useful application in other types of electron discharge vessels differing from the types described above.

While I have illustrated and described the invention as embodied in electron tubes I do not intend to be limited to the details shown, since various modifications and structural changes may be made without departing in any way from the spirit of my invention.

Without further analysis, the foregoing will so fully reveal the gist of my invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What I claim as new and desire to secure by Letters Patent is:

1. In an electron discharge vessel for emitting electrons into the space outside said vessel an electron transmitting window in the wall of said discharge vessel, said electron transmitting window comprising a thin wall portion of an electron transmitting electrically non-conductive material, and a flat accelerating electrode provided with a plurality of apertures for the passage of electrons being arranged adjacent to that surface of said thin wall portion which is inside said electron discharge vessel covering said surface and thus supporting said thin wall portion of said electron discharge vessel.

2. In an electron discharge vessel for emitting electrons into the space outside said vessel an electron transmitting window in the wall of said discharge vessel, said electron transmitting window comprising a thin wall portion of an electron transmitting electrically non-conductive material, and a thin accelerating electrode plate provided with a plurality of apertures for the passage of electrons being arranged adjacent to that surface of said thin wall portion which is inside said electron discharge vessel covering said surface and thus supporting said thin wall portion of said electron discharge vessel.

3. In an electron discharge vessel for emitting electrons into the space outside said vessel an electron transmitting window in the wall of said discharge vessel, said electron transmitting window comprising a thin wall portion of an electron transmitting electrically non-conductive material, and a flat accelerating electrode grid forming a plurality of grid apertures for the passage of electrons being arranged adjacent to that surface of said thin wall portion which is inside said electron discharge vessel covering said surface and thus supporting said thin wall portion of said electron discharge vessel.

4. In an electron discharge vessel for emitting electrons into the space outside said vessel an electron transmitting window in the wall of said discharge vessel, said electron transmitting window comprising a thin wall portion of an electron transmitting electrically non-conductive material, and a flat accelerating electrode provided with a plurality of apertures for the passage of electrons being arranged adjacent to that surface of said thin wall portion which is inside of said electron discharge vessel, said flat accelerating electrode being sealed to said thin wall portion forming one single unit with the same and thus supporting said thin wall portion of said electron discharge vessel.

5. In an electron discharge vessel for emitting electrons into the space outside said vessel an electron transmitting window in the wall of said discharge vessel, said electron transmitting window comprising a thin wall portion of an electron transmitting electrically non-conductive material, and a thin accelerating electrode plate provided with a plurality of apertures for the passage of electrons being arranged adjacent to that surface of said thin wall portion which is inside said electron discharge vessel, said thin accelerating electrode plate being sealed to said thin wall portion forming one single unit with the same and thus supporting said thin wall portion of said electron discharge vessel.

6. In an electron discharge vessel for emitting electrons into the space outside said vessel an electron transmitting window in the wall of said discharge vessel, said electron transmitting window comprising a thin wall portion of an electron transmitting electrically non-conductive material, and a flat accelerating electrode grid forming a plurality of grid apertures for the passage of electrons being arranged adjacent to that surface of said thin wall portion which is inside said electron discharge vessel, said flat accelerating electrode grid being sealed to said thin wall portion forming one single unit with the same and thus supporting said thin wall portion of said electron discharge vessel.

7. In an electron discharge vessel for emitting electrons into the space outside said vessel an electron transmitting window in the wall of said discharge vessel, said electron transmitting window comprising a thin glass wall portion, and a flat accelerating electrode provided with a plurality of apertures for the passage of electrons arranged inside said discharge vessel adjacent to said thin glass wall portion sealed to and forming one single unit with the same and thus supporting said thin wall portion of said electron discharge vessel.

8. In an electron discharge vessel for emitting electrons into the space outside said vessel an electron transmitting window in the wall of said discharge vessel, said electron transmitting window comprising a thin glass wall portion, and

and thus supporting said thin wall portion of said electron discharge vessel.

18. In an electron discharge vessel for emitting electrons into the space outside said vessel an electron transmitting window in the wall of said discharge vessel, said electron transmitting window comprising a thin lead glass wall portion, and a flat accelerating electrode grid consisting of an alloy having the same temperature coefficient as said lead glass of which said thin lead glass wall portion consists, said flat accelerating electrode grid forming a plurality of grid apertures for the passage of electrons and being arranged inside said discharge vessel adjacent to said thin wall portion, sealed to said thin wall portion and forming one single unit with the same and thus supporting said thin wall portion of said electron discharge vessel. 15

19. In an electron discharge vessel for emitting electrons into the space outside said vessel an electron transmitting window in the wall of said discharge vessel, said electron transmitting window comprising a thin lead glass wall portion, and a thin accelerating electrode plate consisting of an alloy comprising mainly nickel, iron, chro- 20 25

mium, and traces of cobalt, said thin accelerating electrode plate being provided with a plurality of apertures for the passage of electrons and being arranged inside said discharge vessel adjacent to said thin wall portion, sealed to said thin wall portion and forming one single unit with the same and thus supporting said thin wall portion of said electron discharge vessel.

20. In an electron discharge vessel for emitting electrons into the space outside said vessel an electron transmitting window in the wall of said discharge vessel, said electron transmitting window comprising a thin lead glass wall portion, and a flat accelerating electrode grid consisting of an alloy comprising mainly nickel, iron, chromium, and traces of cobalt, said flat accelerating electrode grid forming a plurality of grid apertures for the passage of electrons and being arranged inside said discharge vessel adjacent to said thin wall portion, sealed to said thin wall portion and forming one single unit with the same and thus supporting said thin wall portion of said electron discharge vessel.

HENRY ALFRED DE PHILLIPS.
